VEHICLE WASHING MACHINE

David Fisher, Los Angeles, Calif., assignor to
Washmobile Corporation, Beverly Hills, Calif.,
a corporation of California

Application July 30, 1949, Serial No. 4,215

Term of patent 14 years

(Cl. D49—1)

To all whom it may concern:

Be it known that I, David Fisher, a citizen of the United States, residing at Los Angeles, in the county of Los Angeles and State of California, have invented a new, original, and ornamental Design for a Vehicle Washing Machine, of which the following is a specification, reference being had to the accompanying drawing, forming part thereof.

In the drawing:

Fig. 1 is a front elevational view of a vehicle washing machine, showing my new design.

Fig. 2 is a top plan view of the washing machine shown in Figure 1;

Fig. 3 is an end elevation of the washing machine, looking in the direction of the arrow 3 of Figure 1; and

Fig. 4 is an end elevation of the vehicle washing machine, looking in the direction of the arrow 4 of Figure 1.

I claim:

The ornamental design for a vehicle washing machine, as shown.

DAVID FISHER.
